(57) **CLAIM**

The ornamental design for an autoclave, as shown and described.

DESCRIPTION

FIG. 1 is a front view of an autoclave;
FIG. 2 is a rear view thereof;
FIG. 3 is a top view thereof;
FIG. 4 is a bottom view thereof;
FIG. 5 is a left side view thereof;
FIG. 6 is a right side view thereof; and,
FIG. 7 is a perspective view from upper right side thereof.
The broken lines are included for the purpose of illustrating portions of the autoclave that form no part of the claimed design.
